CARTON

Reynolds Guyer, St. Paul, Minn., assignor to
Waldorf Paper Products Company, St. Paul,
Minn., a corporation of Minnesota

Application July 31, 1946, Serial No. 687,283

2 Claims. (CL 229—43)

1

My invention relates to an improvement in cartons wherein it is desired to provide a carton structure which may be effectively sealed.

Rectangular cartons are usually provided with closing flaps on at least one end thereof which may be folded into superimposed relation to form an end seal. One end of such cartons can usually be tightly sealed over a mandrel inserted into the carton. In view of the presence of the mandrel, sealing pressure can be applied to press the flaps firmly together. However, it has been difficult to seal the other ends of these cartons as the contents of the carton will usually not resist external pressure. Two short flaps on two opposed walls are usually folded into coplanar relation, and flaps on the remaining opposed walls are folded over the coplanar flaps and sealed thereto. When the coplanar flaps are moistened with adhesive they have a tendency to curl down into the carton. External pressure against the closure tends to accentuate this tendency of the inner flaps to curl.

It is the object of the present invention to provide a flap structure which is capable of withstanding external pressure. When applied to the opposed flaps, first folded into coplanar relation, the tendency of these flaps to curl into the interior of the carton is also obviated. As a result a more effective seal can be accomplished.

It has usually been considered impractical to adhere two scored carton surfaces together with the scores in registry and to fold the double thickness portions about the common line of fold. When two such surfaces are folded in unison there is a tendency for the two plies to separate as the outer ply must stretch to some extent or the inner ply must compress together to some extent at the line of fold. Accordingly where carton walls have been formed of double thickness it has been usual practice to either terminate one thickness of the material at the line of fold, or else to leave the two plies unadhered on one side of the line of fold to permit relative sliding movement. I have found, however, that this previous difficulty may be used to advantage in overcoming the difficulty in sealing carton closing flaps together on the last sealed end of a carton.

A feature of the present invention lies in the provision of a carton having two opposed side walls of double thickness and in forming closing flaps on these walls which are also of double thickness. Each of the walls is provided with a score line, which score lines are adhered sub-

2

stantially in registry. This double thickness of the flaps at the score line tends to resist the force tending to fold these flaps into coplanar relationship. As a result the flaps have a tendency to raise or to straighten out relative to the side walls rather than to fold down into the carton when adhesive is applied thereon or when external pressure is exerted against the flaps.

A feature of the present invention lies in providing a carton having a pair of opposed flaps to be folded into coplanar relation and to form these flaps of double thickness material on both sides of the score line connecting the flaps to the carton. The score lines of the individual layers of stock are individually formed. As a result considerable force is required to fold these flaps into coplanar relationship and as a result these flaps are capable of resisting pressure exerted against flaps overlying the coplanar flaps to produce an effective seal.

These and other objects and novel features of my invention will be more clearly and fully set forth in the following specification and claims.

In the drawings forming a part of my specification:

Figure 1 is a diagrammatic view of a carton blank showing my new design.

Figure 2 is a perspective view of the end of my carton before the sealing operation of the last carton end.

Figure 3 is an elevational view of my carton partly in section showing the double thickness flaps folded into coplanar relationship.

Figure 4 is a view similar to Figure 3 showing the carton completely sealed.

The carton A, which is illustrated in the drawings, is of a type usually known as a Britewood Carton. This type of construction is employed because of the fact that two opposed walls of such a carton are usually at least partially of double thickness. The carton is shown as having a bottom wall 10 foldably connected along parallel fold lines 11 and 12 to front and rear wall panels 13 and 14. The front panel 13 is connected along parallel fold lines 15 and 16, preferably at right angles to the fold line 11 to side wall panels 17 and 19, respectively. The rear panel 14 is connected along fold lines 20 and 22 preferably in alignment with the fold lines 15 and 16 to side wall panels 23 and 24.

The side wall panels 17 and 19 are connected along fold lines 25 and 26, respectively, to side wall flaps 27 and 29, which connect the bottom wall 10 to the side walls of the carton. The side wall panels 17 and 19 and the front panel

13 are connected along a common fold line 30 to end closure flaps 31, 32, and 33, respectively. The side wall panels 23 and 24 and the rear wall panel 14 are connected along a common fold line 34 to sealing flaps 35, 36, and 37, respectively.

2 In forming the carton A the front and rear wall panels 13 and 14 are folded into right angular relation to the bottom 10 so that the side wall panels 17 and 23 overlap and the side wall panels 19 and 24 overlap. Adhesive is applied between the panels 17 and 23 and between the panels 19 and 24 to hold the side walls in right angular relation to the front and rear walls 13 and 14. The flaps 27 and 29 are also folded horizontally and are sealed adhesively to the bottom panel 10 either interiorly or exteriorly thereof.

3 The adhesive securing the side wall panels 17 and 23 together extends between the flap 31 and the flap 35 so as to adhesively secure these flaps together. Similarly adhesive is applied between the flap 32 and the flap 36 to adhesively secure these flaps together. As a result not only the side walls, but two of the end closing flaps are 25 of double thickness.

4 The score line 30 registers with the score line 34, or substantially registers therewith to permit the folding of the double thickness flaps along a common line of fold.

5 In sealing the carton the double thickness flaps are folded as illustrated in Figure 3 into coplanar relationship. Because of the connection between the two thicknesses of material on both sides of the common line of fold, there is considerable resistance to the folding of these flaps. In folding the double thickness flaps it is necessary that the outer plies 35 and 36 stretch somewhat adjacent the line of fold or that the carton material between the inner plies 31 and 32 compresses somewhat at the line of fold. As a result there is a decided tendency for the folded flaps to fold into their original upright position and considerable pressure is required to fold them beyond the horizontal position shown in Figure 3.

6 Adhesive is applied either to the upper surfaces of the flaps 35 and 36 as they appear in Figure 3, or to the under surface of the next adjacent flap 33 so as to adhere these flaps together. Adhesive is also applied between the flaps 33 and 37 to adhere these flaps together. The tendency for the inner flaps to curl into the carton when moistened with adhesive is greatly reduced or obviated and this tendency is opposed by the greater tendency of the double thickness flaps to fold into upright vertical position. Furthermore considerable external pressure can be applied to the flap 37, tending to seal the various flaps securely together.

7 It will be noted that the flaps 31 and 32 are slightly shorter than the flaps 35 and 36 to which they are connected. This structure is fol-

8 owed in order to insure the proper meeting of the flaps at the center of the carton, but is not essential. Furthermore, while I have shown the shorter flaps 31 and 32 connected to the side wall panels 17 and 19, obviously the other flaps 35 and 36 could be shortened to lie inwardly of the longer flaps 31 and 32. I have further described the panel 13 as comprising the front of the carton and the panel 14 as comprising the back of the carton, but this arrangement is merely for the purpose of convenience as any of the walls of the carton could be considered the front thereof.

9 In accordance with the patent statutes, I have 15 described the principles of construction and operation of my carton, and while I have endeavored to set forth the best embodiment thereof, I desire to have it understood that obvious 20 changes may be made within the scope of the 25 following claims without departing from the spirit of my invention.

10 I claim:

11 1. A carton comprising a series of carton walls 20 connected together, and closing flaps foldably connected to said walls and foldable into superimposed relation, two opposed of said flaps on 25 two opposed of said walls being foldable into superimposed relation and the remaining flaps being foldable thereover, said two opposed walls 30 comprising two thicknesses of carton stock, said double thickness carton stock extending on both sides of the line of fold connecting said two opposed flaps to their respective walls said two opposed flaps and their respective two opposed walls 35 being secured together throughout their opposed faces on both sides of the line of fold.

36 2. A carton comprising a series of side walls 40 foldably connected together, two opposed side walls being formed of two panels extending throughout their width in surface contacting relation and adhered together throughout their length, each of said panels having an end flap thereon connected thereto along registering fold lines, said flaps on said panels being adhered in 45 surface contacting relation, said flaps being arranged in coplanar relationship, and closing flaps on the remaining side walls folded over said first mentioned closing flaps and adhered thereto to form a carton closure.
